DESIGN FOR A RAZOR BLADE RECEPTACLE OR SIMILAR ARTICLE

Irving S. Bodkin, New York, N. Y.

Application April 19, 1939, Serial No. 84,379

Term of patent 14 years

To all whom it may concern:

Be it known that I, Irving S. Bodkin, a citizen of the United States, residing in New York, county of New York, State of New York, have invented a new, original, and ornamental Design for a Razor Blade Receptacle or Similar Article, of which the following is a specification, reference being had to the accompanying drawing, forming a part thereof.

Fig. 1 is a perspective view of the razor blade receptacle or similar article showing my new design; and

Fig. 2 is a top plan view of the razor blade receptacle or similar article illustrated in Fig. 1.

I claim:

The ornamental design for a razor blade receptacle or similar article, substantially as shown.

IRVING S. BODKIN.
